C. M. STUBER,
HOOTHOUSE OR PROTECTOR FOR YOUNG PLANTS,
APPLICATION FILED MAY 10, 1919,
1,326,113. Patented Dec. 23, 1919.

UNITED STATES PATENT OFFICE.

CLYDE M. STUBER, OF BETHLEHEM, PENNSYLVANIA.

HOTHOUSE OR PROTECTOR FOR YOUNG PLANTS.

1,326,113.

Specification of Letters Patent. Patented Dec. 23, 1919.

Application filed May 10, 1919. Serial No. 296,211.

To all whom it may concern:

Be it known that I, CLYDE M. STUBER, a citizen of the United States, residing at Bethlehem, in the county of Northampton and State of Pennsylvania, have invented 5 certain new and useful Improvements in Hothouses or Protectors for Young Plants, of which the following is a specification, reference being had to the accompanying 10 drawings.

This invention relates to an improved protector or hothouse, particularly adapted for housing young plants, for instance, bean, strawberry, cabbage, pepper and various 15 other plants, too numerous to mention in this application.

Heretofore it has been found that the blossoms of various young plants, when planted in the early spring, have been considerably 20 damaged, owing to the frost, and also owing to the rain, too much of which causes rotting or decay of the fruit. Beans when planted in the early spring sprout in a very short while, for instance in about two weeks, and 25 if there be heavy frost, the vines will be practically destroyed, in which case the crop will be almost nothing, which will not pay for the planting.

Therefore, the invention aims to provide a 30 protector or hot-house, whereby these disadvantages may be overcome, in order to attain a very large crop.

In order to accomplish this result, the invention aims to provide a housing, which 35 consists of a frame, or several frames adjacent each other, and including glass panels arranged in the sides and top of the frames, for inclosing or housing young plants, thereby keeping out the frost, as well as preventing 40 the rain from beating down the vines.

When utilizing several housings or protectors, it is the aim of the invention to provide a hot-bed, on which the frames may rest, say for instance, several of them in parallelism to each other, the adjacent side glasses of which being removed, and certain 45 of them supported in positions bridging the spaces between the frames of the housing, thereby providing a housing extending over 50 two or more rows of young plants.

It is known that protectors or hot-houses for young plants have been heretofore used. However, in such devices the frames have 55 been constructed of woodwork, which necessarily complicates the construction and also after one season, or possibly two seasons of

the use of such protectors, the woodwork becomes more or less rotten or decayed, in which case entirely new protectors or possibly new frames are necessary. These conditions result in considerable expense in running a truck farm or in planting a small garden. Therefore, in connection with the present invention it is the aim to provide a protector consisting of a metallic frame, for 60 instance of galvanized iron, for the support of the glass panel. At the start it is possible that a protector of this kind including a metallic frame would involve more expense than a protector including a wooden frame. 70 However, should a metallic frame be employed, which is the design of the present invention, it is conclusive that such a frame could be used for a number of years, and in the end, the expense would be considerably 75 reduced by the use of a metallic frame. Furthermore, the metallic frame is more substantial and practical, owing to the above reasons, and also neater in appearance. Furthermore, metallic frames are easier to 80 handle, and should they become bent they can be straightened, whereas in the case of a wooden frame, it would require considerable work to repair the corner bars of the frame. 85

In certain other protectors the panels are arranged, as inclined toward each other, thereby providing a protector which is V-shaped in cross-section, which it has been found prevents the tops of the young plants 90 from spreading. In the present invention, it is the aim to provide a three-panel protector, that is two sides and the top, whereby the tops of the plants may easily spread. A further advantage attained in providing 95 a protector having two sides and the top is that the protectors may be arranged adjacent each other in parallelism, the adjacent sides of the protectors being removed, and certain of the sides or panels used to bridge 100 the spaces between the frames of the protectors, in order to provide a housing or protector over several rows of plants. In the devices which are V-shaped in cross-section, as heretofore mentioned, this result 105 is not attainable.

A further advantage gained by the protector having the two sides and the top is that the top panel may be held in a slightly raised position at one edge, not only allowing the rain to run off, but also permit of 110 ventilation.

The invention further aims to provide means for supporting the top panel in a slightly raised position, the same means being also employed to engage the top panel, 5 and lift one edge thereof out of engagement with the frame.

The invention further aims to provide a galvanized sheet metal frame, that is constructed of corner angle bars, so brazed or 10 riveted together that the glass panels may be slid into position, the angular recesses of such angle corner bars acting as guides, for the reception of the edges of the glass panels.

15 It may be mentioned that the frames of the protector may be used without the glass panels, that is the frame may be arranged over the row of plants, and a piece of light carpet or rags may be thrown over the 20 frame, that is when the plants are real young, thereby keeping out the hot sun, particularly during the hottest part of the day. However, in the morning, that is after the frost has gone, the glass panels may be used, 25 and then again in the late evening, and until the next morning. In this way the frost is prevented from injuring the plants, that is when they are real young, and then by covering the frames with the rags or 30 carpet during the hottest part of the day, the plants are protected from the hot sun. It has been found that this method of protecting plants enables a truck farmer or 35 gardener to produce a large crop at the end of the season.

While the design and construction at present illustrated and set forth is deemed preferable it is obvious that as a result of a reduction of the invention to a more practical 40 form for commercial purposes, the invention may be susceptible to changes, and the right to these changes is claimed, provided they are comprehended within the scope of what is claimed.

45 The invention comprises further features and combination of parts, as will be hereinafter set forth, shown in the drawings, and claimed.

In the drawings:

50 Figure 1 is a view in perspective of a single protector or hot-house constructed in accordance with the invention.

Fig. 2 is a similar view showing the top panel slightly raised and supported in such 55 raised position by means of a prop.

Fig. 3 is a perspective view of several of the protectors or hot-houses arranged adjacent each other in parallelism, supported upon a hot-bed and in such a use of the device 60 it will be noted that the adjacent panels of the protectors have been removed, one of said removed panels being supported by means of transverse members, in order to bridge the space between the protectors.

65 Fig. 4 is an enlarged detail view of the

frame of the protector, showing the detail construction of the grooves, for the reception of the panels.

Fig. 5 is a detail view of the prop.

Fig. 6 is a detail view of one of the supports to hold one of the panels as bridging the space between the adjacent protectors. 70

Referring to the drawings, 1 designates the frame of a protector as a whole. This frame comprises elongated bottom, and top 75 corner bars 2 and 3. It is to be noted that these bars are constructed of galvanized iron angle pieces. The bottom corner angle pieces are arranged whereby their angular recesses face inwardly, certain of the flanges 80 of said pieces being positioned horizontally to limit the glass panel in its downward movement, when slid into position in the frame.

The top angle corner pieces are correspondingly arranged, so that the top glass panel 4 may rest within the angle pieces, in such wise as to prevent the flatwise movement of the panel. The frame also consists of the end bottom and top corner pieces 5 and 6 of galvanized iron. It is to be noted 90 that the bottom end corner pieces 5 are arranged reversely to the side corner pieces 2, in fact certain of their flanges extend downwardly, in order to engage into the soil. 95 However, the upper end corner pieces 6 are disposed correspondingly to the longitudinal upper side corner pieces 3, whereby the top panel may rest therein, in the same manner as it does upon the longitudinal side 100 corner pieces. Owing to this construction of the end top corner pieces the top panel is prevented from movement lengthwise. The frame also includes the inclined end corner pieces 7 and 8. These pieces are constructed 105 from galvanized channel iron, and are disposed in such wise that the inclined side panel glasses 9 may be slid into the channels of these pieces, that is from the top of the frame, and owing to the bottom corner 110 pieces 2 being disposed so that certain of their flanges are horizontal, said horizontal flanges limiting the inclined side panel glasses in their movements downwardly. In view of this, it will be seen that the frames 115 can be moved from one place to another, without the inclined side panel glasses falling from the frame.

A protector constructed along such lines may be used to house or inclose a row of 120 young plants, and in view of the fact that the protectors are open at both ends, several protectors may be arranged adjacent each other endwise, in order to cover a long 125 row of young plants in such a case the end of the row of protectors being closed by a board or the like improvised for this purpose, that is through the night, and if found necessary, through certain parts of the day. However, it has been found very 130

essential to leave the ends of the protector open, the protectors when used in a series end to end, so as to permit of a thorough ventilation through the protectors lengthwise. It is obvious that when so arranging a row of protectors, it is possible to slightly raise every other top panel, and owing to the remote ends of the entire length of protectors being open, the interior of the 10 protectors may be thoroughly ventilated, in other words, allowing the air to thoroughly circulate about the plants. Furthermore, owing to the particular shape of the protectors in cross-section, that is having the 15 two sides and the top, the tops of the plants are allowed to spread, and owing to the thorough circulation, it has been found that the young plants will quickly thrive. Say, for instance, three protectors 20 are employed, arranged adjacent each other endwise. In this case, the central top panel of the central protector may be slightly raised, and then by reason of the remote ends of the end protectors being open, air 25 is allowed to thoroughly circulate through the protectors. The air will enter the ends and rise from the opening of the central protector, the top panel having been slightly raised.

30 In order to hold the top panel raised an improved prop has been devised, which is formed from a single length of wire, which is shown in Fig. 5, and this prop consists of a body part 10, the ends of which are 35 provided with U-shaped parts or yokes 11 and 12. The U-shaped part or yoke 11, it will be noted, straddles the vertical flange of one of the longitudinal corner pieces, while the U-shaped part or yoke 12 straddles 40 one longitudinal side edge of the top glass panel, as shown in the drawings, thereby supporting the top panel slightly raised. It is obvious that by gripping a part of the yoke 12, and inserting the end of the longer arm 45 of the yoke 11 between the vertical flange of one of the upper longitudinal corner pieces, and the edge of the glass panel, it is possible to raise the panel sufficiently, to permit it to be grasped by the hands, so that 50 the prop may be positioned in place.

In some instances, protectors of this character are used in plurality, and in connection with hot-beds. For example, the hot-bed is buried or countersunk into the soil, 55 and consists of wood frames, and into the hot-bed 13, requisite soil is deposited, for the planting of young plants, such as beans, strawberry plants and numerous other plants. Cross pieces or supports 14 are 60 then arranged across the hot-bed and the protectors are supported on the crosspieces. When so used, it is the aim to construct a hot-bed so as to permit of a series of protectors arranged endwise adjacent each 65 other and in two rows in parallelism with

each other. When so used the adjacent panels of the protectors are removed, and certain of the removed panels are supported on supporting members 15, the hooked ends 16 of which engage the upper longitudinal 70 corner pieces of the frames of the protectors. These supporting pieces are constructed from single lengths of wire, having hooks on their ends.

As previously stated, the frames of the 75 protectors may be used without the panels, and in such instances an old piece of carpet may be thrown over the frame, in order to cover the young plants and protect them from the hot sun. Old rags may be employed 80 for this purpose, but after the plants have reached sufficient growth, the rags or carpet may be removed, and the panels substituted.

Not only can strawberry plants be protected from too much rain, which causes them to rot, but they and other similar plants can be protected from the pests (that very often spoil all the crops) by simply applying window screens or other wire 85 meshwork or fabric on the protecting frames, in lieu of the glass panels. In other words, frames having wire fabric pieces stretched thereover may be constructed in shapes or contours corresponding to the 90 glass panels, and may be substituted in lieu of the glass panels, supported by the angle or channel bar of the protecting frame. For instance one or two, or all three of the 95 glass panels may be moved, and the wire 100 fabric coverings applied in their stead. It is obvious that any suitable wire fabric or meshwork, without holding the frame may be disposed on the protecting frames in lieu of the glass panels. While this wire fabric 105 means of covering the frames is not shown in the drawings, nevertheless it is obvious that such a covering can be employed, and furthermore the invention should not be limited to the glass panels alone, since it 110 is obvious that wire fabric coverings would be within the limits of what is claimed.

The invention having been set forth, what is claimed as new and useful is:

1. In a plant protector, the combination 115 with a plurality of protectors comprising frames arranged adjacent each other in parallelism, said frames when so arranged having remote downwardly and outwardly inclined side panels, a top panel for each 120 frame, and a glass panel bridging the space between the frames, means for supporting the panel which bridges from one frame to the other.

2. In a plant protector, a plurality of 125 protectors arranged endwise adjacent each other, and lengthwise adjacent each other in parallelism, said protectors comprising frames, side panels for said frames, the adjacent side panels being removable 130

and certain of which panels when removed being supported to bridge the space between adjacent parallel frames, means to support such bridging removed panels, top panels 5 for the frames, the frames having their upper portions provided for the reception of said top panels.

3. In a plant protector, a plurality of 10 protectors arranged endwise adjacent each other, and lengthwise adjacent each other in parallelism, said protectors comprising frames, side panels for said frames, the adjacent side panels being removable and certain of which panels when removed being 15 supported to bridge the space between adjacent parallel frames, means to support such bridging removed panels, top panels for the frames, the frames having their upper portions provided with means for the 20 reception of said top panels, and means to support the top panels of the frames in slightly raised positions, whereby the interior of the protectors may be ventilated.

4. In a protector, the combination with 25 a frame comprising upper and lower longitudinally extending angle corner pieces, of end corner pieces having channels and having their lower ends engaging within the lower longitudinal angle pieces, and their 30 upper ends engaging on the exterior of the upper longitudinal angle pieces, transparent panels engaging the end corner pieces and being supported by the lower longitudinal angle pieces, a top panel engaging the upper 35 longitudinal angle pieces, said end corner pieces being inclined downwardly and outwardly, connections between the upper ends of the end corner pieces, and transverse angle pieces connecting the corresponding 40 ends of the lower longitudinal angle pieces, each of said transverse angle pieces having one of its flanges extending downwardly to embed into the ground, to prevent movement of the protector.

45 5. In a protector, the combination with a frame comprising longitudinally extending top and bottom angle corner pieces, of downwardly diverging channels pieces connecting the ends of the longitudinally extending angle pieces, panels engaging said channel pieces, the lower longitudinally extending angle pieces being disposed to re-

ceive the lower edges of the panels for supporting the panels, upper transverse end pieces connecting the corner channel pieces, 55 a top panel engaging within the upper longitudinally extending angle pieces, and transverse lower angle pieces connecting the corresponding ends of the lower longitudinally extending angle pieces, said lower 60 transverse angle pieces having certain of their flanges extending downwardly to bite into the soil to prevent movement of the protector.

6. A plant protector comprising upper 65 and lower longitudinally extending angle pieces, end corner pieces connected to the ends of the upper longitudinally extending angle pieces, said end corner pieces being positioned on the exteriors of the upper longitudinally extending angle pieces and having 70 channels for the reception of panels, the lower ends of the end corner pieces being secured to the interiors of the lower longitudinal pieces, whereby the lower longitudinal pieces may support the panels, a top panel engaging the upper longitudinal angle pieces, upper transverse end pieces connecting the diverging corner pieces, and transverse lower angle pieces connecting the corresponding ends of the lower longitudinal 75 angle pieces and having certain of their flanges embedding into the soil.

7. A plant protector frame comprising 80 longitudinally extending top and bottom 35 longitudinal pieces, downwardly diverging end corner pieces, connecting the longitudinally extending top and bottom pieces, and having guides, side panels engaging said guides, a top panel engaging the upper longitudinally extending pieces, upper transverse end pieces connecting the upper ends 90 of said corner pieces, and angle pieces connecting the corresponding ends of the lower longitudinally extending pieces, and having 95 means extending downwardly adapted to embed into the soil.

In testimony whereof I hereunto affix my signature in the presence of two witnesses.

CLYDE M. STUBER.
